UNITED STATES PATENT OFFICE.

RUDOLPH COOPERSMITH, OF MONTREAL, QUEBEC, CANADA, ASSIGNOR OF ONE-HALF
TO ABRAHAM RUCHE, OF PHILADELPHIA, PENNSYLVANIA.

SPRING-MATTRESS.

1,382,344.

Specification of Letters Patent. Patented June 21, 1921.

Application filed December 19, 1919. Serial No. 346,032.

To all whom it may concern:

Be it known that I, RUDOLPH COOPERSMITH, a citizen of the United States of America, and resident of the city of Montreal, in the Province of Quebec and Dominion of Canada, have invented certain new and useful Improvements in Spring-Mattresses, of which the following is a full, clear, and exact description.

10 This invention relates to improvements in bed bottoms and the object of the invention is to provide a bed bottom of what is commonly known as the coil spring or spiral spring type which will be absolutely noiseless and in which the sagging will be reduced to a minimum.

According to this invention the bed bottom or spring comprises a rigid bottom frame and a floating top frame with a series 20 of spiral, helical springs mounted between. The springs are connected by means of helical springs which extend from side to side of the floating frame. The spiral, helical or upright springs are specially formed in their 25 uppermost turns to hold them against creeping on the transverse helical springs and to hold themselves against enlargement in use. The rigid bottom frame is a grid of thin metal bars disposed on edge and notched into 30 one another.

In the drawings which illustrate the invention;—

Figure 1 is a fragmentary, plan view of the device.

35 Fig. 2 is a side elevation of one of the upright springs.

Fig. 3 is a fragmentary, perspective view illustrating a section of the bottom grid.

Referring more particularly to the drawings, 11 designates the side member of the rigid bottom frame which may be of any suitable construction and which carries transversely disposed bars 12 supporting longitudinally disposed bars 13. The transverse bars may, if desired, be twisted or bent in any suitable manner at their extremities for attachment to the frame 11. These bars are of thin metal and are disposed on edge so as to have a maximum resistance to flexion 50 by a vertically acting load. Preferably the transversely disposed bars 12 are deeper than the longitudinally disposed bars 13 and may also be thicker. The adjacent edges of the bars are notched as at 14 so that they may be

let into one another and thereby support one another against swinging or twisting. Preferably the lower edges of the longitudinal bars and the upper edges of the transverse bars are notched in order that the tensile strength of the lower tensioned edges of the transverse bars may be unimpaired. It may also be found advisable to make the notches in the transverse bars shallower than in the longitudinal bars in order to preserve as much as possible the strength in the transverse bars. These bars 12 and 13 are provided on each side of each intersection with apertures 15 through which the lower ends of upright springs 16 may be threaded.

These upright springs 16 are of the usual spiral, helical or conical type and are arranged large end uppermost in the usual manner. The uppermost convolution of each spring 16 is provided with diametrically opposite, outwardly extending, open loops 17 of such length that when the springs are in position the loops of one row of springs will be spaced a short distance from the loops of the springs in the next row. At the commencement of the uppermost convolution of each spring the wire thereof is downwardly offset, as shown at 18, and the extremity of the wire forming the last convolution of the spring is looped around the wire at or immediately above this offset, as shown at 19. It will further be noticed that the offset and loop 19 are formed approximately midway between the loops 17, so that any tendency to enlarge the spring, due to tension applied to the loops 17, will cause the loop 19 to slide on the wire in a downward direction. As the loop 19 is formed above the offset 18 this is impossible and the spring is, therefore, held against enlargement.

95 The springs 16 are arranged in rows longitudinally and transversely of the frame 11 as clearly shown in Fig. 1, being threaded at the lower ends through the bars 12 and 13 and disposed with their loops 17 extending longitudinally of the structure. Preferably those springs at the ends of the longitudinal rows have only one loop 17 projecting away from the end of the structure. The springs at the ends of the longitudinal and transverse rows are connected to the usual floating frame 20 by any suitable means such as the clips 21.

A series of helical springs 22 of comparatively small diameter are disposed transversely of the structure and are connected at their ends to the longitudinal side members of the frame 20. These springs are threaded through the loops 17 of adjacent springs 16 to hold the springs 16 against swinging either transversely or longitudinally of the structure. In a properly constructed device the springs 22 will exert a slight tension in the uppermost convolutions of the springs 16 in the longitudinal direction of the device so that there will be no looseness or rattling. The extremities of the loops 17 are also preferably of such size that the wire of the springs 22 will fit tightly in the loops 17 and the loops will fit tightly between the turns of the springs 22. The springs 22, in addition to holding the springs 16 against swinging, also hold them against revolution which would disconnect them from the bars 12 and 13.

It has been discovered that one of the reasons why the ordinary coil spring mat- 25 tress creaks and cracks is because of the very short connecting members between the springs, with the result that a small amount of spring compression produces a very con- siderable angular or bodily movement of the 30 connecting pieces, with the result that con- siderable creaking results. In some con- structions of this type the springs are con- nected by intersecting members arranged 35 diagonally with respect to the frame, with the result that the compression of any one spring produces relative sliding movement between the connectors which gives rise to a creaking or cracking sound. In the present structure there is no sliding movement 40 and practically no angular movement at points of intersection, with the result that no creaking or cracking can be possible. The transverse connecting members, that is, the springs 22 are easily elongated so that 45 localized pressure on the device produces only local compression of the springs 16 and does not result in sloping the whole surface of the structure to the locality of pressure.

Having thus described my invention, what 50 I claim is:—

1. In a device of the class described, a rigid bottom frame comprising a grid formed of longitudinal and transverse members arranged on edge and let into one 55 another, helical springs maintained in upright position on said frame, the members of the frame being apertured adjacent their intersection for the reception of the lower ends of the upright springs, a top frame and 60 helical springs stretched between opposite sides of said frame and connecting the uppermost convolutions of adjacent upright springs, said helical springs being arranged to hold the upright springs against revolution in the rigid body frame.

2. A device according to claim 1 in which the longitudinally disposed members are notched on their lower edges and the transversely disposed members are notched on 70 their upper edges, the longitudinally disposed members being of less depth than the transversely disposed members.

3. A device according to claim 1, in which the upright springs are provided with dia- 75 metrically opposite loops with which the helical springs engage, a single helix of the spring engaging and connecting the loops of adjoining upright springs.

4. In a device of the character described, 80 a bottom frame, helical springs maintained in upright position on said frame and pro- vided with diametric opposite loops, a top 85 frame and horizontally disposed helical springs stretched between opposite sides of said top frame and threaded through the loops of said upright springs in such manner that each loop of the upright springs pinches one turn of the horizontal spring threaded therethrough and is in turn 90 pinched between turns of the said horizontal spring, the arrangement being such that the upright springs are tensioned in their diametric direction by the horizontal 95 springs threaded therethrough.

In witness whereof I have hereunto set my hand.

RUDOLPH COOPERSMITH.
